Inventor:

George R. Brown,

by *Alfred S. Lunt*
His Attorney.

UNITED STATES PATENT OFFICE.

GEORGE R. BROWN, OF BRIDGEPORT, CONNECTICUT, ASSIGNOR TO GENERAL ELECTRIC COMPANY, A CORPORATION OF NEW YORK.

ELECTRIC CUT-OUT.

Application filed September 17, 1925. Serial No. 57,037.

The present invention relates to electric cut-outs and more especially to cut-outs of the plug type.

It is common practice to employ the three wire system for supplying electric current for ordinary house lighting purposes, one wire being neutral between the potentials of the other two. The fuse blocks or cut-outs employed for protecting such systems have quite uniformly been provided with three plug receptacles, one for each circuit wire, although the neutral wire was regarded as carrying no voltage and no current. Today it is believed to be better practice to directly ground the neutral wire, and in order to make such grounded connection of the neutral wire effective, it is necessary that all sections thereof either be connected together or else all sections thereof individually grounded.

The object of my invention is the provision of a sealing plug whereby the three wire cut-out blocks now installed may have their neutral line contacts permanently connected by merely screwing it home in the neutral receptacle.

One embodiment of my invention is shown in the accompanying drawing in which Fig. 1 is a plan view of a three wire cut-out block with my sealing plug in place; Fig. 2 is an axial section of the sealing plug detached; and Fig. 3 is an isometric perspective of the same.

The cut-out block shown in Fig. 1 is a well known article of commerce and comprises a porcelain base 1 with three receptacles 2, 3 and 4 on its upper face and in each receptacle are a screw shell contact 5 and a center contact 6 respectively provided with binding post extensions 7 and 8 for coupling of the sections of the line wires thereto. The screw shell contact 5 and the center contact 6 are spaced out of normal conductive relation and requiring ordinarily to be connected by the insertion of a fuse plug (not shown), whereby the current is directed through the fusible element thereof. The contacts 5 and 6 of the middle or neutral receptacle 3 are positively connected

electrically by screwing home therein the sealing plug shown detached in Figs. 2 and 3.

The plug comprises a sheet metal thimble 9 with its cylindrical wall threaded corresponding to the threaded terminal 5 and its lower end 10 flat and unpunched so that when the plug is screwed into the threaded terminal 5, electric contact is made therewith through the sides of the plug and through the lower end 10 engaging the center contact 6.

The means for facilitating the insertion of the sealing plug and preventing its removal consists of a metal disk 11 secured inside thereof and provided with two spaced and oppositely directed teeth 12 struck up therefrom whereby two abrupt shoulders 13 are presented for engagement with a screw driver when turned right-handedly and cause the plug to be screwed home, but by reason of the inclines 14 on the opposite sides of the teeth, turning of the screw driver left-handedly does not cause a backing out of the plug since there is no coupling engagement between them. The toothed disk 11 is held in the plug thimble 9 by solder or by frictional contact between the parts.

While I have shown the best embodiment of the invention known to me, I do not desire to be restricted thereto.

What I claim as new and desire to secure by Letters Patent of the United States, is:

A sealing plug for electric cut-outs comprising a screw-threaded metal thimble adapted to make shunting contact between the center and screw shell contacts of a cut-out, and a metal disk provided with oppositely inclined spaced teeth secured at the inner end of said thimble whereby it may be operated by a screw driver into permanently fixed operative position in said screw shell contact.

In witness whereof, I have hereunto set my hand this eleventh day of September 1925.

GEORGE R. BROWN.
